GUY WORTHINGTON RHODES, OF AUBURN, NEBRASKA.

TWO-CYCLE GAS-ENGINE.

1,111,495.

Specification of Letters Patent. Patented Sept. 22, 1914.

Application filed June 27, 1913. Serial No. 776,124.

To all whom it may concern:

Be it known that I, GUY WORTHINGTON RHODES, residing at Auburn, county of Nebraska, State of Nebraska, a citizen of the 5 United States, have invented certain new and useful Improvements in Two-Cycle Gas-Engines; and I do hereby declare the following to be a full, clear, and exact description of the invention, such as will enable others skilled in the art to which it pertains to make and use the same.

My invention relates to improvements in gas engines and more particularly to the two-cycle type.

15 One of the objects of the invention is to provide a gas engine having means for admitting the explosive mixture and expelling the burned gases at approximately the time when the piston has reached the end of its outward stroke.

Another object is to provide a gas engine with means whereby the passage of gases into and out of the storage, explosion and compression cylinders is positively controlled at all times.

Another object is to provide a gas engine in which the piston, the inlet and exhaust valve of the piston cylinder and the gas inlet distributing valve are operatively connected together.

Another object is to provide a gas engine with a piston which operates both in the explosion and gas compression chamber.

Another object is to provide a gas engine 35 in which the waste of the explosive mixture is prevented by suitable means which properly times the exhaust with relation to the inlet.

Another object is to provide a gas engine 40 which will work equally as well at high as at low speeds.

Another object is to provide a gas engine which is simple, inexpensive, durable, compact and economical in construction and exceedingly easy and effective in operation.

Referring to the drawings:—Figure 1 is a central vertical section showing the several parts in the positions they assume when the piston is at the end of its upward or compression stroke. Fig. 2 a central vertical section, similar to Fig. 1, showing the several parts in the positions they assume when the piston is at the end of its downward or explosion stroke. Fig. 3 a side elevation 55 partly broken away and in section. Fig. 4 an end elevation partly broken away and in

section. Fig. 5 a detail side view of the inlet and exhaust valve of the piston cylinder. Fig. 6 a detail sectional view of the inlet and exhaust valve of the piston cylinder. Fig. 7 a sectional view of the gas inlet valve. Fig. 8 a top plan view of the slidable cylindrical valve.

In the drawings, in which similar reference characters denote similar parts throughout the several views, 1 represents my gas engine having a casing made preferably in four parts or sections 2, 3, 4 and 5 secured together by means of bolts 6 or other suitable means. The part 4 constitutes 60 the piston cylinder of the engine and is provided with walls 7 having a space 8 between them for water, or any other suitable cooling medium, by which the piston cylinder and the parts therein are kept cool. The 65 lower end of the piston cylinder is enlarged as shown at 9 and forms, with the piston hereinafter described, a gas compression chamber 10 and just above this enlargement 70 the piston cylinder is provided with a series of exhaust ports 11 and at its upper end is provided with a series of inlet openings 12. The series of inlet ports 12 communicate with a circular passage 13 at the upper portion of the piston cylinder and the series 75 of exhaust ports 11 communicate with a circular passage 14 which is in communication with an exhaust pipe 15. The circular passage 13 is connected by means of a pipe 16 80 with a casing 17 having inlet passage 18 for the admission of gas from a carburetor, or any other suitable source of supply, and a port 19 connects said casing 17 with the gas compression chamber 10 in the enlarged portion 9 of the piston cylinder. The pipe 16 85 serves to retain the combustible gas under initial pressure so that it will instantly flow into the combustion chamber upon the registering of the inlet ports of the piston cylinder with the inlet ports of the cylindrical valve.

A rotatable gas inlet and distribution valve 20 is provided in the casing 17 which controls the supply of gas, and when in the position shown in full lines, in Fig. 9, it 90 supplies gas through the port 19 to the gas compression chamber in the piston cylinder, when said valve is in the position shown by dotted line 21 it allows the passage of gas 95 from the gas compression chamber into pipe 16, and when in the position shown by dotted lines 22, it cuts off the supply of gas.

The part 5 of the casing constitutes the cylinder head and is provided with walls 24 having a space 25 between them for water, or any other suitable cooling medium, by which it is kept cool, a chamber 26 in which is located spaced disks 27 and 28 secured on shafts 29 and 30 respectively mounted in bearings 31. The cylinder head extends into the upper end of the piston cylinder, terminating in a convex end 32 just above the inlet ports 12 of the said cylinder, and is spaced from the inner wall of the cylinder as shown at 33. A spark plug 34, of any well known make, is secured in the convex end 32 of the cylinder head.

A cylindrical valve 35 provided with a series of inlet ports 36 and exhaust ports 37 is slidably mounted in the piston cylinder with its upper end extending between the inner wall of the cylinder and the outer wall of the cylinder head and is operatively connected to the disks 27 and 28 by means of a link 38 the lower end of which is pivoted at 39 to said valve 35 and the upper end pivoted between the disks 27 and 28 on a pin 40 eccentrically mounted in said disks by which a reciprocatory movement is imparted to the valve 35 when said disks are rotated to cause the inlet and exhaust ports 36 of the piston cylinder to be moved into and out of registry with the ports of the said valve 35. The exhaust ports of the piston cylinder and the valve 35 are preferably made larger than the inlet ports of the piston cylinder and valve 35 for the purpose of allowing the exhaust ports to open in advance of the inlet ports but they may be made of the same size if desired. The piston 41 is spaced from the walls of the enlarged portion 9 of the piston cylinder and extends into the lower end of the valve 35 and is provided with an enlarged portion 42 slidably contacting with the wall of the enlarged portion 9 of the piston cylinder. Packing rings 43 are provided in the cylinder, the cylinder head and piston to insure tight joints between them. The convex surface 32 of the cylinder head serves to deflect the combustible gas, introduced through the inlet ports, downward in a compact body and assists in the expulsion of the exploded gases through the exhaust ports, and the convex surface of the piston serves to deflect or direct the exploded gases through the exhaust ports. The parts 2 and 3 of the casing constitute the crank casing 44 of the engine and 45 is an outlet or drain for lubricant in the part 2.

A crank shaft 46 is mounted in the crank casing in bearings 47 and is operatively connected to the piston by means of the connecting rod 48 the upper end of which is pivoted on a pin secured to the piston and the lower end pivoted on the crank shaft. The shaft 29 and the crank shaft 46 are operatively connected by means of a shaft 49, the upper end of which is provided with a bevel gear 50 which engages a bevel gear 51 on shaft 29 and the lower end is provided with a bevel gear 52 which engages a bevel gear 53 on the crank shaft, and the valve 20 is operatively connected to the shaft 49 by means of a worm gear 54, on shaft 55 of the said valve, which engages a worm 56 on the shaft 49. The shaft 49, bevel gears 50, 51, 52, 53, worm gear 54 and worm 56 are inclosed by a casing 57.

A fly wheel 58 is provided on one end of the crank shaft 46 and the other end with a removable handle 59 to be used for starting purposes.

The operation of the engine is as follows: Assuming that an explosion has just taken place in the combustion chamber as the piston starts on the outward stroke the rotary gas inlet and distributor valve 20 opens the port 19 permitting the gas to flow from the carburetor through the inlet passage 18 into the gas compression chamber 10 and as the piston starts on the return stroke the valve 20 closes the inlet passage 18 from the carburetor and at the same time opens the port 19 and allows the gas to enter the initial compression pipe 16 where it is confined by the valve 20 closing the entrance at or about the time the piston reaches the end of its inward stroke. At this time the previous charge of gas in the cylinder has been compressed by the piston and as it is exploded it drives the piston outward and as the piston reaches the extent of its outward stroke the function of the slidable valve 35 comes into play and said valve is lowered causing the exhaust ports to register, thus permitting the exploded gases to escape through the exhaust passages or ports and the same downward movement of the valve 35 causes the inlet ports to register thus permitting the combustible gas to pass from the initial compression pipe 16 through the inlet ports into the combustion chamber and as it strikes the convex surface of the cylinder head it is deflected downward in a more or less compact body thus completing the expulsion of the exploded gases by driving them down and out through the open exhaust ports, the exhaust gas is then shut out and the combustible gas confined within the explosion chamber by means of the slidable valve 35 rising so as to put both the exhaust and inlet ports out of registry, said action taking place at or about the time the piston starts on its inward stroke. The charge of gas is now ready to be compressed with the return stroke of the piston, after which it is exploded and in turn forced out by the incoming of the next charge which has filled the initial compression pipe in the manner before described.

I do not desire to be understood as limited

ing myself to the specific details of construction and arrangement as herein described and illustrated, as it is manifest that variations and modifications may be made in the 5 features of construction and arrangement in the adaptation of the device to various conditions of use without departing from the spirit and scope of my invention and improvements. I therefore reserve the right 10 to all such variations and modifications as properly fall within the scope of my invention and the terms of the following claims.

What I claim is: -

1. In a gas engine, a piston, a piston cylinder having inlet and exhaust ports, a slideable cylindrical valve therein having inlet and exhaust ports, a compression chamber, an initial gas storage chamber communicating with the inlet ports of the cylinder, a 15 valve between said chambers, controlling the inlet of gas into the compression chamber and the passage of gas therefrom into the initial storage chamber, a power shaft with which said piston is connected and a shaft 20 operatively connecting said slideable cylindrical valve, valve and power shaft, substantially as described.
2. In a gas engine, a piston cylinder having inlet and exhaust ports and enlarged at 25 its lower end, a piston operable in said piston cylinder and having an enlarged portion which fits and contacts with the enlarged portion of the piston cylinder and forms therebetween a gas compression chamber, a cylindrical valve, mounted in such manner as to be out of contact with the enlarged portions of the piston cylinder and piston, slideable between the upper portion of the piston cylinder and the piston 30 and having inlet and exhaust ports, an initial gas storage chamber communicating with the inlet ports of the cylinder, a gas inlet valve between said compression chamber and storage chamber controlling the inlet of gas 35 into the compression chamber, between the enlarged portions of the piston cylinder and piston, and the passage of gas into the initial storage chamber, a power shaft and a shaft operatively connecting said slideable

cylindrical valve, gas inlet valve and power shaft, substantially as described.

3. In a gas engine, a piston cylinder having inlet and exhaust ports and enlarged at one end forming a gas compression chamber, a gas storage chamber communicating with the inlet ports of the cylinder, a cylindrical slideable valve in said piston cylinder having inlet and exhaust ports, a single piston which fits and operates within the slideable cylindrical valve having an enlarged portion which fits and operates within the enlarged portion of the piston cylinder, and serves to compress the gas in the gas compression chamber, a rotatable gas inlet valve adapted to supply gas to the gas compression chamber and from thence supply it to the piston cylinder and means operatively connecting the cylindrical valve, piston and rotatable gas inlet valve, substantially as described.

4. In a gas engine, a piston cylinder having inlet and exhaust ports and enlarged at its lower end, a cylindrical slideable valve, of substantially the same diameter from end to end, in said piston cylinder having inlet and exhaust ports, a piston operatively mounted within said cylindrical slideable valve and having an enlarged lower end, a gas compression chamber formed between the enlarged portion of the piston cylinder and the enlarged portion of the piston, a gas storage chamber communicating with the inlet ports of the cylinder, a passage forming a communication between the gas compression chamber and gas storage chamber, a gas inlet valve in said passage, for controlling the supply of gas to the gas compression chamber and from the gas compression chamber to the gas storage chamber, and means operatively connecting said slideable cylindrical valve, gas inlet valve and piston, substantially as described.

In testimony whereof, I affix my signature in the presence of two witnesses.
